(57) **CLAIM**

The ornamental design for a greeting card pick strip panel, as shown and described.

DESCRIPTION

FIG. 1 is a perspective view of the greeting card pick strip panel of the present invention, showing greeting cards in the various pockets.

FIG. 2 is a perspective view of the greeting card pick strip panel of FIG. 1, without greeting cards.

FIG. 3 is a front elevation view of the greeting card pick strip panel of FIG. 2.

FIG. 4 is a rear elevation view of the greeting card pick strip panel of FIG. 2.

FIG. 5 is a right side elevation view of the greeting card pick strip panel of FIG. 2.

FIG. 6 is a left side elevation view of the greeting card pick strip panel of FIG. 2.

FIG. 7 is a top plan view of the greeting card pick strip panel of FIG. 2.

FIG. 8 is a bottom plan view of the greeting card pick strip panel of FIG. 2.

FIG. 9 is a perspective view of a second embodiment of the greeting card pick strip panel of the present invention.

FIG. 10 is a front elevation view of the greeting card pick strip panel of FIG. 9.

FIG. 11 is a rear elevation view of the greeting card pick strip panel of FIG. 9.

FIG. 12 is a right side elevation view of the greeting card pick strip panel of FIG. 9.

FIG. 13 is a left side elevation view of the greeting card pick strip panel of FIG. 9.

FIG. 14 is a top plan view of the greeting card pick strip panel of FIG. 9; and,

FIG. 15 is a bottom plan view of the greeting card pick strip panel of FIG. 9.

The broken lines are for the purpose of illustrating the environment of the design only and form no part of the claimed design.

1 Claim, 9 Drawing Sheets
